UNITED STATES PATENT OFFICE.

CHARLES CUSTER ROBINSON, OF RICHMOND, VIRGINIA.

DIMMER SYSTEM.

Application filed March 19, 1924. Serial No. 700,446.

To all whom it may concern:

Be it known that I, CHARLES CUSTER ROBINSON, a citizen of the United States, residing at Richmond, in the county of Henrico and State of Virginia, have invented certain new and useful Improvements in Dimmer Systems, of which the following is a specification.

This invention relates to dimmer and like systems, and particularly to means for actuating dimmer switches singly and in groups.

Generally stated, the invention contemplates the use of a dimmer switch, or the like, having a definite range of movement, a presetting member having a similar range of movement and means for locking it in any adjustment, a floating connection between the two which normally leaves each free to be moved independently of the other, but which connection is capable of being confined so that it constrains the switch and presetting member to related or proportional movement, and some normally inactive means for so confining the floating connection.

By using a series of the units just described and connecting the confining means, so that they may be actuated in unison, I provide a device of peculiar utility. Any dimmer may be adjusted manually at any time, and to any extent, independently of the others. Any or all the presetting members may be set for a new effect while the dimmers themselves all remain undisturbed; and, at any time thereafter, a single actuator may be operated to bring all the dimmers to the settings corresponding to the adjustments of the presetting members. All the dimmers arrive at their final positions simultaneously. Furthermore, the angular positions of the presetting member and the corresponding position of the dimmer handle, in the preferred form of the device, are coincident at the end of the operation just described, so that the position of the dimmer handle and of the preset handle are read against the same scale. This facilitates manipulation as it permits direct comparison of the positions of the two elements.

While I describe the invention as applied to dimming switches, it is available for use for similar and related purposes. I use and prefer as the floating connection a link or lever having a floating fulcrum, with means

for positively centering said fulcrum, but other mechanical movements may be substituted as will be apparent to those skilled in the art.

The preferred embodiment of the invention is illustrated in the accompanying drawings, in which:

Fig. 1 is a vertical sectional view showing one switch unit and the mechanism for centering the floating fulcrum;

Fig. 2 is a plan view of the same, partly in section;

Fig. 3 is a section on the line 3—3 of Fig. 1;

Fig. 4 is a front elevation of a plurality of switch units assembled with an actuator for the fulcrum centering means common to all of them.

The various switch elements and their actuating mechanisms are individually supported on corresponding angle members 6, and a master actuating member, common to all of the switch units, is mounted on other angle members 6, the members 6 being part of any suitable framework not shown in detail.

A single switch unit will first be described.

Bolted to the angle members 6 is an insulating base or plate 7 provided with the usual dimmer or rheostat contacts 8, arranged in two arcuate series. The exact construction of the rheostat is not material and is not illustrated.

Projecting forward from the angle members 6 is a plate 9, which serves as a support for the moving parts of the switch unit, and which, at its forward end, carries an arcuate member 10, designed to serve as an indicator dial for both the dimmer lever and the preset lever, and also to serve as a latch sector for the latter. It is provided with graduations 11, as shown, and with a series of latch notches 12 for the purposes stated.

Each arcuate member 10 also carries a front plate section 13, which collectively form the front plate or housing of the switch mechanism. Each plate 13 is provided with a slot 14 for the dimmer lever, and a slot 15 for the preset lever.

The dimmer switch arm 16 is provided with the usual resilient contacts 17, and is fixed at 18 on a shaft 19, which turns in a bearing in the plate 9. Fixed to the other end of the shaft 19, by means of a nut 20, is the dimmer handle 21 which projects for-

ward through the slot 14, and which is provided with an index or pointer 22, co-acting with the scale 11. Consequently, the dimmer switch arm can be moved to any desired position by moving the handle lever 21.

Swiveled on the shaft 19 is a preset lever 23, which extends through the slot 15 and carries at its upper end a latch 24, which engages the notches 12 and which has a small index extension 25 also readable against the graduations 11. The preset lever 23 may be swung to any desired position when the latch 24 is released, and may be latched thereby in any desired position.

15 A floating lever 26 is pivoted at 27 to the dimmer switch arm 16, and has a pin and slot connection 28 with the preset arm 23, the center line of the slot forming part of this pin and slot connection, passing 20 through the center of the pivot connection 27.

25 Fixed on the side of the floating lever 26 is a base or stud 29, whose distance from the pivot 27 is equal to the radial distance between the shaft 19 and the pivot 27. Consequently, if the stud 29 be moved to such a position that its axis is coincident with the axis of the shaft 19, and if it be held there, the preset lever 23 and the dimmer switch arm 16 will be brought into and maintained in alignment.

30 It follows from the above that if the stud 29 be left free, the dimmer switch arm 16 may be moved to any desired position by 35 moving the handle lever 21 while the preset arm remains latched in any position. Similarly, the preset arm 23 may be set to any desired position while the dimmer switch arm 16 and its handle 40 lever 21 remain at rest in any position within their range of movement. However, if the stud 29 be forced into alignment with the shaft 19, the dimmer switch arm 16 must move to the setting indicated by the 45 presetting lever 23.

To center the stud 29 I make use of a pair of cam plates 30, 31, which are mounted on shafts 32, 33, extending parallel with the shaft 19 above and below the plates 9. The 50 shafts 32 and 33 are connected together by sector gears 34 and 35, so that they move in unison.

55 They might be actuated in any desired manner but I prefer that the actuating lever be on an axis aligned with the shaft 19. To permit this, I mount the master actuating lever 36 on stub shaft 37 and connect this by means of sector gears 38 and 39 with the shaft 32. Consequently, the lever 36 operates both shafts 32 and 33 in unison, and, when actuated, swings the cams 30, 31 toward each other.

60 Such motion of the cams causes one or another of them to engage the stud 29 and 65 force it to alignment with the shaft 19,

at which point the stud is engaged also by the other cam and positively confined against displacement.

Several switch units are assembled side by side as indicated in Fig. 4, and the cams 30, 31 of each switch unit are mounted on one pair of shafts 32, 33, actuated by a single master lever 36. In order to retain the master lever 36 in its normal upward position, it is provided with a counter-weight 40, as indicated in the drawings. Any equivalent mechanism, such as a spring, might be substituted, the purpose being to retain the master lever 36 in such position that the cams 30, 31 are retracted, leaving 75 the floating levers 26 of all the switches free.

80 The master lever being at its upper normal position with the cams 30 and 31 retracted, as shown, it is possible to set the preset lever 23 at any desired position, by releasing the latch 24 and moving the lever, and then allowing the latch to reengage. Before or after setting the lever 23, it is 85 possible to adjust individual dimmer switch 90 arms 16 by moving their corresponding handles 21.

95 By actuating the master handle 36, all the levers 21 will be brought into coincidence with the corresponding preset levers 23, and all will arrive at these positions simultaneously, for the reason that they complete their movements just as the studs 29 reach the alignment with the shaft 19.

100 It will be observed that the position in which the preset lever 23 is set determines the position to which the corresponding handle 21 will be moved by the master lever. Consequently, the setting of the preset levers is a direct indication of the positions to be assumed by the levers 21, and the 105 positions of both levers may be indicated on a single scale. This feature is one of substantial importance from the manipulative standpoint.

110 The device is of simple and inexpensive construction in all its parts, and the various switch units may be multiplied indefinitely, permitting any desired number of switches to be handled.

115 As stated, other mechanical movements capable of forming a floating connection between two related parts might be substituted for the floating lever shown, but I prefer this because of its simplicity and the directness of its action.

120 What is claimed is:

125 1. The combination of a dimmer switch; a presetting member; means for fixing said member in adjusted positions; a connection between said switch and member normally floating to permit independent movement of each, but capable of being confined, and when confined, serving to constrain said switch and member to related movement;

130

- and means operable to confine said connection.
2. The combination of a dimmer switch; a presetting member; means for fixing said member in adjusted positions; a connection between said switch and member having a floating fulcrum permitting independent movement of each, said connection serving, when said fulcrum is moved to a fixed position, to establish a definite relation between the positions of said switch and member; and means for moving said fulcrum to said fixed position.
3. The combination of a pivoted switch member; a preset member pivoted on a common axis therewith; means for holding said preset member in adjusted positions; a link connecting said members and having a pivotal connection with one and a sliding connection with the other; a fulcrum on said link so positioned thereon as to be coaxial with the common axis of said members when the latter are similarly adjusted, of means operable to move said fulcra of all said links to alignment with said axes simultaneously.
4. The combination with a plurality of dimmer units, each including a switch member, a presetting member, means for fixing said presetting member in adjusted positions, a connection between said members, normally floating to permit independent adjustment of each, but capable of being confined, and when confined serving to establish a definite relation between the positions of said members, of means operable to confine all of said connections simultaneously.
5. The combination with a plurality of dimmer units, each including a switch member, a presetting member, means for fixing said presetting member in adjusted positions, a connection between said members having a floating fulcrum permitting independent movement of each, said connection serving when said fulcrum is moved to a definite position to establish a definite relation between the positions of said switch and member, of means operable to move said fulcra of all said switch units to such definite positions simultaneously.
6. The combination with a plurality of dimmer units, each including a pivoted switch member, a preset member pivoted on a common axis therewith, means for holding said preset member in adjusted positions, a link connecting said members and having a pivotal connection with one and a sliding connection with the other, a fulcrum on said link so positioned thereon as to be coaxial with the common axis of said members when the latter are similarly adjusted, of means operable to move said fulcra of all said links to alignment with said axes simultaneously.
7. The combination of a pivoted switch member having a handle; a preset member for predetermining positions of the switch member, pivoted on a common axis therewith and having a handle, said handles being so arranged that they are alined when the switch is in the position determined by the preset member; a latch for holding said preset member in the adjustments effected by its handle; a cover structure having apertures for the passage of said handles and provided with a graduated scale against which the positions of said handles may be read; a floating linkage connecting said members; a floating fulcrum on a part of said linkage so positioned as to be coaxial with the common axis of said members when the switch is in the position determined by the preset member; and means operable to move said fulcrum to the last-named position.
8. The combination with a plurality of dimmer units, each including a pivoted switch member having a handle, a preset member for predetermining positions of the switch member pivoted on a common axis therewith and having a handle, said handles being so arranged that they are alined when the switch is in the position determined by the preset member, a latch for holding said preset member in the adjustments effected by its handle, a floating linkage connecting said members, and a floating fulcrum on a part of said linkage so positioned as to be coaxial with the common axis of said members when the switch is in the position determined by the preset member; of a cover structure having apertures for said handles and provided with graduated scales, one for each pair of associated preset and switch handles, arranged to indicate directly the relative adjustments of said handles; and means operable to move said floating fulcra of all said linkages to alinement with said axes simultaneously.

In testimony whereof I have signed my name to this specification.

CHARLES CUSTER ROBINSON.
